(57) **CLAIM**

The ornamental design for a three-sided indoor ball, as shown and described.

DESCRIPTION

FIG. 1 is a perspective view of a three-sided indoor ball of the present invention;

FIG. 2 is a top plan view of the three-sided indoor ball shown in FIG. 1, which is the same as the bottom view;

FIG. 3 is a front view of the three-sided indoor ball shown in FIG. 1, which is the same as elevation views at 120 degrees and 240 degrees;

FIG. 4 is a rear view of the three-sided indoor ball shown in FIG. 1;

FIG. 5 is a perspective view of a second embodiment of a three-sided indoor ball of the present invention viewed from above, which is the same as the first embodiment shown in FIG. 1 except for having a stranded exterior surface;

FIG. 6 is a plan view of the three-sided indoor ball shown in FIG. 5;

FIG. 7 is a front view of the three-sided indoor ball shown in FIG. 5, which is the same as elevation views at 120 degrees and 240 degrees; and,

FIG. 8 is a rear view of the three-sided indoor ball shown in FIG. 5.
